O. B. WALKER.

INSULATOR.

APPLICATION FILED DEC. 28, 1911.

1,032,715.

Patented July 16, 1912.

UNITED STATES PATENT OFFICE.

ORAL B. WALKER, OF TAYLORVILLE, ILLINOIS.

INSULATOR.

1,032,715.

Specification of Letters Patent. Patented July 16, 1912.

Application filed December 28, 1911. Serial No. 668,290.

To all whom it may concern:

Be it known that I, ORAL B. WALKER, a citizen of the United States, residing at Taylorville, in the county of Christian and

5 State of Illinois, have invented certain new and useful Improvements in Insulators, of which the following is a specification, reference being had therein to the accompanying drawing.

10 This invention relates to telegraph or telephone poles, and has particular reference to the means for supporting the cross arms upon said poles.

One of the objects of this invention is the 15 production of efficient means for firmly holding the cross-arms in engagement with the poles so as to prevent the same from sagging when a strain is placed thereon while stringing the wires.

20 Another object of this invention is the production of efficient cross arms wherein the same consists of a plurality of transversely extending members having their ends connected together whereby the two 25 arms will be firmly held together.

25 With these and other objects in view this invention consists of certain novel constructions, combinations, and arrangements of parts as will be hereinafter fully described 30 and claimed.

In the drawings:—Figure 1 is a front elevation of a telegraph pole showing one of the cross arms in section. Fig. 2 is a top plan view of the cross arms showing the telegraph pole in section. Fig. 3 is a side elevation of the telegraph pole showing the cross arms in section. Fig. 4 is a side elevation of a telegraph pole partly in section showing the manner of connecting the cross arms to 40 said poles. Fig. 5 is a side elevation of the telegraph pole showing the cross arm in elevation having the insulators removed therefrom. Fig. 6 is an enlarged sectional view showing the manner of connecting the insulator support to one of the cross arms. Fig. 7 is an enlarged sectional view of one 45 of the insulator supporting bolts showing the manner of connecting the bracing rods by means of the common connecting nut.

50 Referring to the drawings by numerals 1 designates the telegraph pole which is provided near the top thereof and upon each side with a transversely extending notch 2 within which are seated the cross arms 3. These 55 cross arms 3 are formed preferably of hollow pipe sections carrying at their respective

ends elbows 4 to which are connected the joining pipe sections 5 for forming a substantially continuous cross arm extending upon both sides of the pole.

60

Insulator supporting bolts 6 are carried by the cross arms 3 and are provided with enlarged heads 7 for holding the insulators 8 firmly in engagement with the bolt 6. These bolts 6 are also provided near their ends with a flared portion 8 which is adapted to rest upon the upper edge of the cross arms 3 for limiting the downward movement of said bolts through said cross arms. A depending stem 9 is carried by each bolt 6, which depending stem extends through the cross arms 3. A nut 10 is threaded upon the lower end of the depending stem 9 of each of the bolts 6 for firmly clamping the bolts 6 in firm engagement with the cross arms. A number of these insulator supporting bolts 6 are used upon each of the cross arms so as to accommodate a number of wires which may be attached thereto. Of course, the usual insulators 8 are formed 80 of the common insulating material and may be of any desired form.

75

85 A pair of brace arms 11 are carried upon each side of the pole and these arms 11 are provided with angularly disposed ends 12 which ends are engaged by a coupler nut 13, which coupler nut secures said angularly disposed end 12 to the under threaded end of one of the central insulating bolts as illustrated in Fig. 1. The brace arms 11 are 90 provided with an eye 14 through which securing bolt 15 passes. An arm 11 extends to each side of the pole as illustrated in Fig. 1, thereby constituting a substantially V-shaped brace, which brace may be readily 95 detached by removing the nuts 13 from the threaded ends of the inner insulating bolts. A pair of arms 11 are secured upon both the back and front of the pole so that the arms upon each side of the post may be firmly 100 braced as illustrated in Fig. 3. Securing bolts 16 pass through the arms 3 for firmly holding these arms in engagement with the pole. By having a plurality of these bolts 16 so passing through the arms, it will be 105 obvious that these bolts will also assist in preventing the arms from sagging upon their sides, as well as the brace arms 11 previously described. It will be further obvious that the cross arms may also be readily 110 removed from the pole by detaching the different sections, and provided only one of the

arms 3 should become damaged, it would not be necessary to replace the entire cross arm, but this damaged arm might be readily removed and a new arm substituted therefor.

5 Of course, it should be understood that the insulators 8 are molded upon the upper ends of the bolts 8, thereby firmly holding the insulators in engagement with the bolts.

What is claimed is:

10 In a device of the character described, comprising a pole having transverse notches on both sides and cross bolt perforations at said notches, pairs of cross arms made of parallel members which engage said pole
15 notches, elbows on the ends of said arms and

connecting joints between them, bolts through said arms and said pole, insulator-supporting bolts on said cross arms, V-shaped braces secured to said pole, the upper threaded portions of said braces being 20 vertical and coupling nuts engaging the upper ends of said braces and the lower ends of said insulator bolts, as specified.

In testimony whereof I hereunto affix my signature in presence of two witnesses.

ORAL B. WALKER.

Witnesses:

G. C. ACHENBACH,
W. E. DEMING.
